UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

IGNITION SYSTEM.

1,406,190.

Specification of Letters Patent. Patented Feb. 14, 1922.

Application filed March 24, 1919. Serial No. 284,806.

To all whom it may concern:

Be it known that I, JOHN H. HUNT, a citizen of the United States of America, residing at Dayton, county of Montgomery, 5 State of Ohio, have invented certain new and useful Improvements in Ignition Systems, of which the following is a full, clear, and exact description.

This invention relates to ignition systems 10 for internal-combustion or explosion engines and has among its objects the provision of an ignition system providing ignition for the engine without the use of primary or secondary batteries.

15 Other and further objects and advantages of the present invention will be apparent from the following description, reference being had to the accompanying drawings, wherein a preferred embodiment of the 20 present invention is clearly shown.

Referring to the drawings:

Fig. 1 is an ignition wiring diagram together with a diagrammatic end elevation of an engine, showing one embodiment of the 25 invention; and

Fig. 2 is a fragmentary wiring diagram showing the changes necessary to be made in the ignition wiring diagram shown in Fig. 1 in order to adapt the ignition system for a 30 single cylinder engine.

Fig. 3 is a side elevation view showing the magneto and generator and connecting gearing.

Referring to the drawings, 20 indicates an 35 internal-combustion engine having a crank shaft 21 carrying a gear 22. Gear 22 cooperates with gear 23 to drive a cam shaft 24, which carries the cams operating the valve rods of the engine, one of which is 40 shown at 25. Shaft 24 carries a timer cam 26 cooperating with a breaker lever 27 pivotally mounted upon a timer cup 28. Lever 27 carries a movable contact 29 normally held in yielding engagement with a stationary contact 30 by means of leaf spring 31 which presses against the timer cup 28 and the breaker lever 27.

Gear 23 cooperates with gear 33 to drive the armature 34 of a generator 35. Brushes 50 36 and 37 conduct the current generated to the main leads 38 and 39 with which lamps or other power translating devices 40 are connected. Excitation for the generator is provided by means of a shunt field winding 41 connected at one end with the brush 36

and at the other with a vibrating switch 42 which in turn is connected by wire 43 with the brush 37. The switch 42 normally short circuits a resistance winding 44 out of the shunt field circuit. A voltage coil 45 60 controls the operation of the switch 42 so that when the voltage across the generator terminals exceeds a certain amount, the switch 42 will be opened, decreasing the field excitation. The windings 44 and 45 65 may be magnetically related so that current passing through the coil 44 will produce a magnetic field in opposition to that produced by current flowing through the coil 45. This relation is indicated by arrows 70 44^a and 45^a.

The relation of the gearing 22, 23 and 33 is such that the generator will be driven at engine speed. Gear 33 is directly connected with a gear 50 which drives a pinion 75 51 at substantially four times engine speed. Gear 51 is mounted upon the shaft 52 of a low tension magneto generator. Shaft 52 carries timer cam 53 and an armature 54, the terminals of which are connected to slip 80 rings 55 and 56. Brushes 57 and 58 co-operate with the slip rings 55 and 56 respectively, to conduct current to the wires 59 and 60 respectively. Armature 54 cooperates with a permanent field magnet 61. 85

Wire 59 is connected with a breaker lever 62 controlled by cam 53. Lever 62 carries a movable contact 63 cooperating with a stationary contact 64 which is connected by wire 65 with the wire 60. Condenser 66 is 90 connected in parallel with the contacts 63 and 64. Spring 67 normally maintains contacts 63 and 64 in engagement under yielding pressure.

Current for ignition purposes during the 95 normal running operation of the engine is supplied from the generator 35. Generator terminal or lead 38 is connected by switch 70 with ignition resistance 71 and ignition coil primary winding 72. Winding 72 is 100 connected to contact 29 by wire 73, timer cup 28, spring 31 and lever 27. Contact 30 is connected by wire 74 with the generator lead 39. Condenser 32 is connected in parallel with the contacts 29 and 30. The 105 secondary ignition circuit includes ignition coil secondary winding 75 which is grounded on the engine frame by wire 76 and is connected with a distributor 77. Distributor rotor 79 cooperates with contacts 79^a to dis- 110

tribute impulses to the various spark plugs of the engine, one being shown at 78.

The magneto generator cooperates with this same ignition coil to produce ignition 5 for starting the engine. Wire 59 is connected with the wire 73 by means of a manually operated switch 80, and the wire 60 is connected with wire 74 by means of an electric switch 81. Switch 81 comprises a winding 10 82 connected across the generator leads 38 and 39, which controls the movement of switch arm 83 normally held by spring 84 in engagement with contact 85. Under certain 15 conditions arm 83 may be attracted away from contact 85 and into engagement with a contact 86 connected by a resistance 87 with the wire 59.

The operation of the invention is as follows:

20 The magneto switch 80 and the primary ignition switch 70 are closed to control the ignition circuits. The engine is started manually and the magneto armature 54 will be rotated at a rate which will cause impulses to
25 be generated of sufficient magnitude for ignition purposes. Each time the contacts 63 and 64 are opened by the cooperation of the cam 53 with the breaker lever 62, the short circuit around the magneto armature 54
30 will be interrupted. Where the magneto and engine are geared four to one, a series of eight equally spaced current impulses will be generated for each revolution of the engine crank shaft 21. If the contacts 29 and
35 30 were maintained apart at all times all of these eight impulses would pass to the primary winding 72. Considering for the moment that contacts 29 and 30 have just opened and that the contact 63 has just
40 moved away from contact 64, an impulse will pass from the magneto armature 54 to the coil winding 72 through the following circuit: slip ring 55, brush 57, wire 59, switch 80, wire 73, coil winding 72, resistance 71,
45 switch 70, wire 38, armature 34, wire 39, wire 74, switch contact 85, arm 83, wire 60, brush 58 and slip ring 56 to magneto armature 54.

50. However, the contacts 29 and 30 are not separated at all times during the operation of the system but are closed during two intervals for each revolution of the crank shaft 21. The relation of the cams 24 and 53 is such that contacts 29 and 30 will remain closed during the time in which every other two of the impulses generated by the magneto are created. It will result therefore that every other of these magneto impulses will be short circuited by the contacts 29 and 60. 30 away from the coil winding 72. Therefore at the time in which the contacts 29 and 30 are closed there will not be sufficient current passing through coil 72 to be transformed by coil 75 into a sparking impulse. 65. Even if that small portion of the short circ-

After the engine has become self-operative, the generator 35 will supply sufficient current for ignition purposes. When the generator is supplying current the primary ignition circuit will include wire 38 leading out from armature 34, switch 70, resistance 71, coil 72, wire 73, contacts 29 and 30, wire 74, main lead 39 which is connected with the armature 34. The contacts 29 and 30 are separated at the proper time in the engine cycle to cause a reduction in current in the coil 72 and the resulting discharge of a sparking impulse from the secondary coil 75 to the distributor 77 and to the spark plugs 78 through the medium of the distributor rotor 79 and the contacts 79^a. 85 90 95

The magneto ignition circuit can be rendered ineffective by opening the switch 80 or automatically upon the reaching of a predetermined engine speed. At such a speed the voltage generated may be sufficient to cause the winding 82 to overcome the tension of the spring 84 and to draw the switch arm 85 away from contact 85 and into engagement with the contact 86. The magneto generator will then be rendered ineffective to deliver current impulses to the ignition coil, and will discharge periodically through the resistance 87. 100 105 110

The relation of the operation of breakers 26 and 62 is such that the timing of the ignition provided by the magneto in combination with the ignition coil is later relative to the engine cycle, than the timing of the ignition provided by the generator in combination with the ignition coil. This arrangement is desirable since it is advantageous to start the engine with the ignition retarded. Thus it will be seen that I have provided means for automatically changing from a relatively retarded starting ignition to a relatively advanced ignition for the running operation of the engine. 115 120

While I have described my invention in connection with a multi-cylinder engine it is apparent that it can be used as well with a single-cylinder engine. The changes in the system which are necessary to change from multi-cylinder to single-cylinder ignition 130

are shown in Fig. 2. The secondary ignition coil winding 75 is grounded at one end and connected directly at the other end with the spark plug of the engine. The only 5 other change that is necessary is to provide the timer cam with one lobe as indicated by the cam 26^a. In this manner the contacts 29 and 30 will be opened only at the beginning 10 of the explosion stroke or slightly before as is the case of advanced ignition. The current impulses generated by the magneto generator will be short circuited away from the ignition coil by contacts 29 and 30, with the exception of those impulses which are 15 generated at the explosion stroke.

From the foregoing description, it is apparent that an ignition system constructed in accordance with the present invention possesses several important advantages, 20 namely: No primary or storage batteries are required, thus eliminating the expense of initial cost and maintenance. Such a system is well adapted for use with a power plant in which no storage batteries are required but the engine is kept running as long as there is any demand for power. It is also advantageous to have the starting ignition retarded relatively to the running ignition in order to facilitate starting, and 25 to have the ignition timing advanced automatically when the engine becomes self-operative.

In the apparatus described, the generator is geared so as to run at engine speed and 30 the magneto so as to run at four times engine speed, but it is to be understood that the invention is not limited to these gear ratios and that other gearing connections could be utilized if desirable.

40 In some types of engines especially high speed automobile engines it might be found desirable to automatically disconnect the magneto from the engine, in order to conserve power and to prevent the magneto from running at an excessive speed after 45 the engine had become self-operative, and the ignition current was being supplied by the generator. In Fig. 3, there is shown a centrifugal device which at a predetermined 50 engine speed will disconnect the magneto from the generator. The gear 50 which drives the magneto pinion 51 is loosely journaled upon a generator shaft 90 and is provided with a clutch member 91 which is 55 adapted to cooperate with a companion clutch member 92 which has a splined driving connection with the shaft 90. The shaft 90 carries a collar 93 upon which are pivotally mounted centrifugal members 94 and 60 95. Each member is provided with a short arm 96 which is connected by link 97 with the clutch member 92. A spring 98 is interposed between the collar 93 and the clutch member 92 and serves, below a predetermined 65 engine speed, to maintain the clutch

member 92 in the position 92^a in which it has driving engagement with the gear 50. At the same time centrifugal members 94 and 95 will occupy 94^a and 95^a, respectively. Above a predetermined engine speed 70 centrifugal force acting upon the weight members 94 and 95 will cause them to overcome spring 98 and to take the positions shown in Fig. 3, whereupon the shaft 90 will be disconnected from the gear 50. 75

While the form of mechanism herein shown and described constitutes a preferred form of embodiment of the invention, it is to be understood that other forms might be adopted, all coming within the scope of 80 the claims which follow.

I claim:

1. In an ignition system, the combination with an engine; of a dynamo-electric-machine for providing starting ignition current; another dynamo for supplying running ignition current; connections between the second dynamo and the engine; relatively high speed gearing between the second dynamo and the first dynamo; and speed 90 responsive means to disconnect said high speed gearing.

2. In an ignition system, the combination with an engine; of a magneto connected therewith for supplying starting ignition; a dynamo connected with the engine for supplying running ignition current; and electro-responsive means to render said magneto inoperative to furnish ignition upon the attainment of a predetermined dynamo 100 voltage.

3. In an ignition system, the combination with an engine; of a low tension magneto connected therewith; an induction coil normally connected with said magneto; a dynamo connected with said engine and co-operating with said coil; and means for disconnecting said magneto from said engine. 105

4. In an ignition system, the combination with an engine; of a low tension magneto 110 connected therewith; an induction coil normally connected with said magneto; a dynamo connected with said engine and co-operating with said coil; and electro-responsive means for disconnecting said magneto 115 from said coil upon the attainment of a predetermined dynamo voltage.

5. In an ignition system, the combination with an engine; of a low tension magneto connected therewith; an induction coil normally connected with said magneto; a dynamo connected with said engine and co-operating with said coil; and speed responsive means for disconnecting said magneto 120 from said engine.

6. In an ignition system, the combination with an engine; of a low tension magneto connected therewith; an induction coil normally connected with said magneto; a dynamo connected with said engine and co- 125

operating with said coil; electro-responsive means for disconnecting said magneto from said coil upon the attainment of a predetermined dynamo voltage; and speed-responsive means for disconnecting said magneto from said engine.

7. In an ignition system, the combination with a current source for starting ignition; of an engine driven generator for running 10 ignition; means cooperating with the first source for providing starting ignition, and with the generator to provide running ignition; and means controlled by the generator for rendering the said first source inoperative.

8. In an ignition system, the combination with a current source for starting ignition; of an engine driven generator for running ignition; means cooperating with the first 20 source for providing starting ignition, and with the generator to provide running ignition; and means controlled by the voltage of the generator for rendering the said first source inoperative.

9. In an ignition system, the combination with an engine; of a plurality of current sources; an ignition coil, means cooperating with said coil and one of said sources to transmit a series of electrical impulses to 30 said coil for ignition purposes; means cooperating with said coil and another of said sources to provide ignition and to render certain of said electrical impulses inoperative.

10. In an ignition system, the combination 35 with a multi-cylinder engine; of a plurality of current sources; an ignition coil; means cooperating with one source and with said coil to provide a series of ignition impulses; means cooperating with another source and 40 with said coil to provide a series of ignition impulses; means for distributing said second series of impulses to the engine and for preventing the passage of certain of the first series of impulses to the engine.

11. In an ignition system, the combination 45 with a multi-cylinder engine; of a plurality of current sources; an ignition coil; means cooperating with one source and with said coil to provide a series of ignition impulses; means cooperating with another source and 50 with said coil to provide a series of ignition impulses and for rendering ineffective certain of the first series of impulses; and means for distributing said second series of

impulses to the engine, while preventing the 55 passage of certain of the first series of impulses to the engine.

12. In an ignition system, the combination with an engine; of a magneto driven thereby; a current source; an ignition coil; a 60 magneto timer for effecting an intermittent flow of a series of impulses to said coil; a second timer for effecting the periodic flow of current from the second current source to the coil and for rendering ineffective cer- 65 tain of the magneto impulses.

13. In an ignition system, the combination with an engine; of a magneto driven thereby; a current source; an ignition coil; a magneto timer for effecting an intermittent 70 flow of a series of impulses to said coil; a second timer for effecting the periodic flow of current from the second current source to the coil and for rendering ineffective cer- 75 tain of the magneto impulses, said second timer being timed in advance of the magneto timer.

14. In an ignition system, the combination with an engine and a plurality of engine driven dynamo-electric-machines; of means 80 cooperating with one machine for providing starting ignition and with another machine for providing running ignition; and means for automatically disconnecting the first mentioned machine from the engine at a pre- 85 determined engine speed.

15. In an ignition system, the combination with an engine; of a low tension magneto having an armature; an induction coil co-operating with said magneto; a dynamo 90 connected with said engine and cooperating with said coil; and means responsive to dynamo voltage to disconnect the magneto from said coil and to provide another path for discharge of the armature current. 95

16. In an ignition system, the combination with an engine; of a low tension magneto having an armature; an induction coil co-operating with said magneto; a dynamo connected with said engine and cooperating 100 with said coil; and means responsive to dynamo voltage to provide another path for discharge of the armature current.

In testimony whereof I affix my signature.
JOHN H. HUNT.
